his Attorney.

UNITED STATES PATENT OFFICE.

FREDERICK B. LOUCKS, OF CHICAGO, ILLINOIS.

DEVICE FOR LOCATING AND RAISING SUNKEN VESSELS.

1,059,548.

Specification of Letters Patent. Patented Apr. 22, 1913.

Application filed January 30, 1911. Serial No. 605,459.

To all whom it may concern:

Be it known that I, FREDERICK B. LOUCKS, a citizen of the United States, and a resident of the city of Chicago, county of Cook, 5 and State of Illinois, have invented certain new and useful Improvements in Devices for Locating and Raising Sunken Vessels, of which the following is a specification.

My invention relates to improvements in 10 devices for locating and raising sunken vessels and has for its object the provision of a device of this character which shall be of simple construction and efficient in operation.

15 The device consists in the combination and arrangements of parts hereinafter described and claimed.

My invention will be best understood by 20 reference to the accompanying drawing which is an elevation partially in section illustrating a device embodying my invention in operative position for locating and raising a sunken vessel.

The preferred form of construction as 25 illustrated in the drawing comprises two cylindrical casings 1 secured to the upper deck of a vessel 2 as shown. A securing member 3 is bolted to the keelson of the vessel and projects upwardly into the bottom portion of each of the casings 1, the 30 said securing member being provided with a securing eye 4 at its upper end. A heavy cable 5 has one end connected to the corresponding eye 4 by means of a swivel connection 6, the said heavy cable being coiled in the corresponding casing as indicated. The other end of cable 5 has a double swivel 35 connection 7 with one end of a lighter cable 8 as indicated. Cable 8 is normally coiled 40 in the corresponding casing above the corresponding heavy cable and its other end is connected by means of a swivel connection 9 with the bottom of a float 10 as indicated. The upper edge of each of the casings 1 45 is provided with a supporting and sealing

lip 11 and each of the floats 10 is provided with an annular supporting and sealing recess 12 adapted to receive said lip.

In use the cables 5 and 8 are coiled in the corresponding casing 1 and the corresponding float seated on said casing with the lip 11 resting in recess 12 thus forming a water-proof sealing for the exclusion of water from said casing.

In case the vessel should sink the floats 55 10 will readily rise from the casings 1 and ride upon the surface of the water being held to said ship by means of the lighter cables 8. Upon discovery of floats 10 the lighter cables 8 may be employed for raising 60 the heavy cables 5 by means of which the vessel itself may be raised to the surface of the water.

Having described my invention what I claim as new and desire to secure by Letters 65 Patent is:

The combination with a vessel, of a casing secured to the deck thereof; a float having a larger part resting on the top of said casing and a smaller part extending into 70 and fitting the bore of said casing and forming a liquid tight joint between the top portion of said casing and such float; a swivel secured to the lower end of such float; a small cable having one end secured to the 75 end of said swivel; a second swivel secured to the other end of said small cable; a second and larger cable having one end secured to said second swivel; a third swivel secured to the other end of said larger cable; and a 80 member rigidly secured to the frame of the vessel and secured to said third swivel, substantially as described.

In testimony whereof I have signed my name to this specification in the presence of 85 two subscribing witnesses.

FREDERICK B. LOUCKS.
